UNITED STATES PATENT OFFICE.

OLIVER McCARTHY, OF MERIDEN, CONNECTICUT, ASSIGNOR TO THE MERIDEN BRITANNIA COMPANY, OF SAME PLACE.

DESIGN FOR COFFIN-TRIMMINGS.

SPECIFICATION forming part of Design No. 16,897, dated September 14, 1886.

Application filed July 26, 1886. Serial No. 209,182. Term of patent 7 years.

To all whom it may concern:

Be it known that I, OLIVER McCARTHY, of Meriden, in the county of New Haven and State of Connecticut, have invented a new Design for Coffin Trimmings; and I do hereby declare the following, when taken in connection with accompanying drawings and the letters of reference marked thereon, to be a full, clear, and exact description of the same, and which said drawings constitute part of this specification, and represent, in—

Figure 1, a front view of a handle-socket; Fig. 2, a face view of a name-plate, the same design; Fig. 3, a transverse section alike in both the plate and socket.

This invention relates to a design for coffin trimmings; and it consists in a plain center having two opposite sides parallel, its two ends elliptical, with a border of corresponding shape, but offset from the plane of the plate, the border representing a concave face surface in transverse section.

A represents the central or plain portion,

the two sides of which are parallel, but terminating at each end in elliptical shape. Around this center A is a plain border, B, offset from the plane of the central border, the border being of equal width and conforming to the shape of the central portion, the face surface of the border representing a concave shape in transverse section, as seen in Fig. 3.

I claim—

The design for coffin trimmings, consisting of the representation of a plain plate, its two sides parallel and terminating at each end in elliptical shape, and having a plain border surrounding it of equal width and corresponding shape, but offset from the plane of the central portion, and so as to present a concave face surface in transverse section, as described, and shown in the accompanying illustrations.

OLIVER McCARTHY.
